(57) **CLAIM**

The ornamental design for a transformable inhaler, as shown and described.

DESCRIPTION

1. Transformable inhaler

1.1 : Top view in folded state

1.2 : Side view in folded state

1.3 : Front isometric view in unfolded state

1.4 : Rear isometric view in unfolded state

1.5 : Left view in unfolded state

1.6 : Right view in unfolded state

1.7 : Front view in unfolded state

1.8 : Rear view in unfolded state

1.9 : Top view in unfolded state

1.10 : Bottom view in unfolded state

(Continued)

In the reproductions, the broken lines show portions of the transformable inhaler that form no part of the claim.
